UNITED STATES PATENT OFFICE.

FREDERICK SIMPSON, OF BOSTON, MASSACHUSETTS.

VOLTAIC GLOVE.

SPECIFICATION forming part of Letters Patent No. 478,293, dated July 5, 1892.

Application filed March 25, 1892. Serial No. 426,426. (No model.)

To all whom it may concern:

Be it known that I, FREDERICK SIMPSON, of Boston, in the county of Suffolk and State of Massachusetts, have invented certain new 5 and useful Improvements in Galvanic Gloves, of which the following is a specification.

My invention has reference to a new and improved application of the well-known principle that copper and zinc when connected 10 and provided with an electrolytic medium will cause a current of electricity to pass from the one element to the other through the medium, and has for its object to apply said principle to gloves, mittens, or other 15 hand-wear, and to this end to provide copper and zinc contacts on the respective fastening-edges of such gloves or mittens, whereby when the said edges are abutted or fastened such contacts will bear against the flesh and 20 an electric fluid generated which will be applied directly to the inner side of the wrist at a point where, as it is well known, the system can be readily acted upon and the most beneficial result attained.

25 My invention consists in providing at each edge of the slit where the glove is opened to receive the hand a strip of copper and a strip of zinc, or, if desired, a series of pieces of the respective metals, and connecting the same 30 with a suitable electric conductor. These strips or contacts may be of any suitable form. For instance, I may compose them of copper and zinc wire netting or gauze to permit greater flexibility. The strips or elements 35 are secured to the glove preferably by the fastenings by which the edges are held together. A cloth binding of suitable material incloses the elements to prevent wear of the glove against the wire-gauze or strip, the portion 40 of the binding adjacent to the flesh having cut-out portions to permit contact of the metal with the flesh of the wrist.

In the drawings I have shown several forms 45 which embody the principles of my invention, although it is obvious that I am not confined to the precise construction therein shown.

Figure 1 shows a glove with the elements of 50 wire gauze or netting; Fig. 2, the elements in the form of strips, and Fig. 3 a plurality of copper and zinc pieces.

The glove *a*, having the customary division *b*, is provided with the elements *c*, placed

substantially parallel with and near to the edges of opening *b*. The elements are connected by suitable electric conductors *g*, which 55 may be wires or other flexible connections. A binding *d*, of any suitable material, surrounds these elements, but is cut away, as at *f*, to permit contact of the elements *c e* with the flesh.

In Fig. 3 I have shown the elements as consisting of a plurality of contact-pieces *c'*, connected, as shown, copper on one side and zinc on the other, which will give greater flexibility, and in some instances may be used to ad- 65 vantage.

It will be unnecessary to herein set forth the beneficial effects of electric currents upon the human system, as such are well understood by those familiar with the art to which 70 this invention relates, the operation of the device also being apparent.

I claim—

1. The improvement in gloves or other hand-wear, consisting of two dissimilar 75 metals, such as copper and zinc, secured to the inner surface of the wrist portion and a connection between the same, whereby when the glove or like article is upon the hand the metals will be in contact with the flesh of the 80 wearer and electric action established, substantially as described.

2. In a glove or like article of hand-wear, wire-gauze strips or plates of copper and zinc secured therein near the edges of the slit or 85 opening for the hand, a connection of some electric conducting material, a suitable binding for the said metals, and suitable openings in said binding to permit contact of the metals with the flesh, substantially as de- 90 scribed.

3. The combination, in gloves or other hand-wear, of copper and zinc elements *c' e'* and connections *g* whereby the contact of the said elements with the flesh will produce currents 95 of electricity, substantially as described.

In testimony whereof I have signed my name to this specification, in the presence of two subscribing witnesses, this 21st day of March, A. D. 1892.

FREDERICK SIMPSON.

Witnesses:

C. F. BROWN,
A. D. HARRISON.
